UNITED STATES PATENT OFFICE.

AMBROSE MATHEWS, OF KEWANEE, ILLINOIS.

PUMP.

SPECIFICATION forming part of Letters Patent No. 237,886, dated February 15, 1881.

Application filed July 22, 1880. (No model.)

To all whom it may concern:

Be it known that I, AMBROSE MATHEWS, of Kewanee, in the county of Henry and State of Illinois, have invented a new and Improved 5 Pump, of which the following is a specification.

This invention relates to that class of submerged pumps that are designed for forcing water to very considerable heights; and it 10 consists of a stem-valve and spring-actuated hollow bail plunger or piston, working in a close-bottomed cylinder, and so arranged that on the upstroke the valve lifts above the piston and admits water to enter the top of the 15 cylinder and flow into and below the piston, while on the downstroke the valve closes down in the top of the piston, so that they act together as a solid piston in forcing water.

Figure 1 is a side elevation of the device. 20 Fig. 2 is a sectional side elevation of the same. Fig. 3 is a rear elevation of the pump-cylinder, showing face of exit-valve. Fig. 4 is a cross-section on line xx , Fig. 2. Fig. 5 is a plan of the reverse of the piston and valve.

25 Similar letters of reference indicate corresponding parts.

In the drawings, A represents the stand-pipe, which may have one or more pump-cylinders connected with it working with alter- 30 nate strokes.

B represents an upright pump-cylinder, preferably made in one casting with its lateral exit-pipe B', said cylinder B being closed at the bottom and open at the top, and being 35 provided at the top with a horizontal brace, C, extending as far as and parallel with the exit-pipe B', and resting against the stand-pipe A, and serving, in combination with the brace-rods B'' and cross-bars B''', that em- 40 brace both cylinder B and stand-pipe A to steady said cylinder B in position.

D is the piston rod or stem, moving vertically in the guide-block A', which projects laterally from the stand-pipe A, and having the 45 pump-spear D' rigidly secured in its lower forked end by bolts and nuts aa . This pump-spear D' has a shoulder or bolster, b, formed on it just below the lower end of the pump stem or rod D, and another shoulder, c, at 50 about half its length, and has its end screw-threaded, as shown at d.

E is a cylindrical hollow piston or plunger,

open at both top and bottom, and fitting closely in the cylinder B, and provided with a cross-bar, f, across its bottom, and an interior annular flange, g, at its top. Said piston E is also provided with a bail, E', and is held in place by the pump-spear D', that passes down through the bail E', and by the screw G, that is entered upward through the cross-bar f into the end 55 of the pump-spear D', and by a spiral spring, H, which encircles said screw G between the head thereof and the cross-bar f, the object of said spring H being to hold said piston E up in place with the bail E' against the shoulder b of the pump-spear D', and with the top 60 of said piston E firmly against and closed by the valve I; and a further object of said spring H is to prevent the jarring and thumping of the piston E when the pump is in operation. 65 The circular valve I is set upon the pump-spear D' just below the shoulder c, and is held immovably in place by screwing a nut, m, up against the under side thereof. In the exit-pipe B' is an ordinary flap-valve, K, fixed on 70 an incline and opening outward and upward into the bore A'' of the stand-pipe A. 75

When this pump is submerged and in operation the upstroke of the piston-rod D lifts and holds the valve I clear from its seat 80 upon the piston E, said piston E being held down, compressing the spring H by the pressure of the water entering the cylinder B, thereby permitting water to enter from the top and fill said cylinder B below the said 85 valve I. On the downstroke of the said rod D the piston E is forced up, by the combined action of the spring H and the pressure of the water in said cylinder B, to meet the descending valve I; and said valve I closing 90 tight in the top of said piston E, the two move together at the downstroke as one solid piston and force the water out through the opening that is controlled by the valve K up through the stand-pipe A. 95

Submerged pumps ordinarily take water in at the bottom of the cylinder, and consequently are very apt to take impure water and mud in from the bottom of the reservoir or river in which the pump is operating, while the cylinder herein shown and described takes water only at the top, and thereby takes and delivers a clearer and purer water—a matter of great importance for water-works, factories, &c.

Having thus fully described my invention, I claim as new and desire to secure by Letters Patent—

1. A force-pump constructed substantially as herein shown and described, consisting of the cylinder B, closed at the bottom, open at the top, and provided with lateral exit B', pump-spear D', provided with fixed valve I, movable hollow piston E, and exit-valve K, as set forth.

2. In a force-pump, the combination, with the pump-spear D', provided with shoulder e and screw-thread d, of the fixed valve I and

nut m, substantially as herein shown and described.

3. In a pump, the combination, with the pump-spear D' and fixed valve I, of the hollow piston E, provided with bail E', cross-bar f, and annular flange g, screw G, and spiral spring H, substantially as herein shown, and for the purpose described.

AMBROSE MATHEWS.
